UNITED STATES PATENT OFFICE.

PAUL H. FRYER, OF PHILADELPHIA, PENNSYLVANIA.

KNITTING MACHINE.

1,416,186.

Specification of Letters Patent. Patented May 16, 1922.

Application filed June 29, 1920. Serial No. 392,660.

To all whom it may concern:

Be it known that I, PAUL H. FRYER, a citizen of the United States, and resident of Philadelphia, county of Philadelphia, and 5 State of Pennsylvania, have invented an Improvement in Knitting Machines, of which the following is a specification.

My invention has for its object the provision of means in a knitting machine for holding the end of a splice thread (when out of operation) in such manner that it will be positively retained in the thread clamp while the needles are caused to engage it during its introduction into the 15 knitted tube in the course of its production, as when introducing a reinforcing or splice thread during the knitting of the sole and back portion of the stocking to the rear of the ankle.

20 My invention is especially applicable to that class of knitting machine in which the central space of the needle cylinder is occupied with a thread clamp and cutter device whose function is to retain the severed 25 ends of a plurality of threads during the introduction of the thread or yarn to the needles under the control of automatically actuated thread guides during the knitting operation; and consists in providing the 30 usual main thread clamp and cutters with an auxiliary thread clamp, preferably gravity actuated, between the said main thread clamp and the needles, for receiving and retaining the custody of the splice 35 thread when out of feeding position and for adding thereupon an additional friction at and during the beginning of the initial feeding preliminary to the interknitting of the yarn or thread into the tubular 40 fabric, to provide a sufficient clamping action to prevent the yarn being drawn out of the main clamp and released from the needles during its said initial introduction from the needles for reinforcing purposes. In 45 the type of machine above referred to there are a number of thread guides for introducing and putting out of action different yarn and those out of action are held by the yarn clamp while the remaining thread or 50 threads are being knitted. When it is required to change the body yarn, it is necessary for the yarn clamp to be positively opened to enable the yarn to be drawn into the clamp and clamped thereby before it 55 is severed. At the time of thus opening the yarn clamp, the reinforcing or splice thread

which is to be introduced is then being drawn through its yarn guide by the rotating needle cylinder and as this must continue for approximately a third of the revolution before the splice thread is interknitted with the tubular fabric, it is essential that the thread shall be at least initially held by other means than the regular yarn clamp to prevent it from becoming disengaged from the needles, because immediately before it would be interknitted, the main yarn clamp is open and the splice thread would, therefore, be disengaged and fail to be properly fed to the machine. By 60 the presence of my improved auxiliary thread clamp, I am enabled to apply sufficient clamping action upon the splice thread that it is not disengaged before the main clamp is readjusted to clamping action 65 and the splice yarn becomes positively interknitted with the tubular fabric.

My invention also consists of improvements hereinafter described whereby the above objects and results are attained, said 80 improvements comprising certain organization and combination of parts which are fully described hereinafter and more particularly defined in the claims.

Referring to the drawing: Fig. 1 is a 85 plan view of a portion of a knitting machine embodying my improvements; Fig. 2 is a side elevation of the same; Fig. 3 is a perspective view of the thread clamping means thereof; Fig. 4 is an elevation showing my 90 improved clamp; Fig. 5 is a cross section taken on line $x-x$ of Fig. 1; and Fig. 6 is a cross section on line $y-y$ of Fig. 1.

2 is the rotating needle head having the usual vertically reciprocating needles 3. The 95 yarns or threads 12 are fed to the needles from the thread guides 4, which are hinged at 5 and adapted to be respectively thrown down into feeding position by springs 4^a under control of levers 6 and suitable pattern 100 control mechanism P.

As shown, there are a plurality of these 105 thread guides and they may be respectively employed for providing threads 12 of different colors or characteristics to be incorporated into the knitted stocking and for special strengthening of the heel and toe portions. Normally, one of these thread guides, at a time, are in operation to supply 110 yarn to the needles while the remainder hold their thread clear of the needles. The ends of the yarns or threads extending from

the guides 4 are held in the clamp 7 within the area of the circular row of needles. 8 is a stationary plate within the needle head and is sustained in position by frame 9. The 5 plate 8 is provided with the usual clamp 7 comprising a clamping jaw 10 which is loosely hinged at 11 and yieldingly pressed downward by spring 10^a to clamp the severed ends of the yarn or threads 12. A cutter 13 is provided for severing the yarn or threads between the clamp 10 and the needles whenever the yarn is thrown out of knitting engagement with the needles by the thread guides 4. The usual means for operating the cutter 13 is a lever 22 which oscillates upon a fulcrum 23 and is normally held upward by spring 24, said lever being operated by pattern mechanism (not shown). This lever also acts upon the pivoted clamp 10 to slightly lift it when introducing the threads into clamping position. All of the foregoing mechanism is common in knitting machines in commercial use and will need no further description.

25 In operation, the thread 12 to be knitted is lowered between the needles 3 and is engaged thereby and knitted in the usual manner. As the needle cylinder rotates, the end of the thread held in clamp 7 is pulled 30 therefrom after the thread has been knitted into the tubular fabric for approximately a third of its circumference and hence at a time when there is no possibility of its being pulled out of the clamp before the knitting therewith begins.

I will now refer to the means for introducing the splice thread 14 and otherwise controlling it, and to which my invention more especially relates. 15 is a thread guide for 40 introducing the splice thread 14 into engagement with the needles. It is pivoted at 16 and combined with means under the control of pattern mechanism P for raising and lowering it at stated intervals, such as when introducing a reinforcing or splice thread 45 into the sole and back of the ankle of the stocking. A stop 17 is employed on the thread guide 15 to limit its downward movement and hold its free or eye end in proper feeding position, as when feeding the splice 50 thread 14 to the needles. The thread 14, after passing through the eye of the thread guide 15, passes between the edge 18 of the stationary plate 8 and the auxiliary clamp 55 plate 19 supported immediately above it and normally resting upon it. This clamp plate 19 has its under edge curved at one end at 60 to permit ready entrance of the thread when taking a position under it. The clamp plate 19 is loosely held in position by a retaining screw 21 which extends through a slot 19^a in the plate (Fig. 4) by which it is attached to the frame 9. In this manner the clamp plate may have slight vertical and oscillatory movement, so that it is free to act

by gravity in its clamping action. Its downward motion is limited by the edge 18 of plate 8. Normally, the splice thread is held in the main clamp 7 on plate 8, thence passes between auxiliary clamp plate 19 and edge 70 18 of plate 8, by which additional clamping action is provided, and thence to the thread guide 15 and normally held above the needles. When this splice thread is to be introduced, the thread guide 15 is lowered by the 75 pattern mechanism with the result of placing the thread 14 between the needles 3, which on advancing pull upon the thread intermediate of its position in the clamp plate 19 and thread guide 15 and because of the additional tension due to the clamp plate 19, the thread is drawn through the guide 15 without being pulled out of the main clamp 7. In this manner sufficient thread 14 is supplied, so that when it is pulled from beneath 80 the clamp plate 19 and ready for knitting, the knitting operation may take place without danger of pulling the end of the thread out of the main clamp 7 before it is interknitted with the tubular knitted fabric; 85 after which, the further rotation of the needle cylinder e causes the end of the thread 14 to be pulled out of the clamp 7, as in the case of the body yarn.

When the splice thread 14 is to be put out of action, the thread guide 15 is raised so that the thread is lifted clear of the needles; and as the needle cylinder rotates, the thread is drawn under both the auxiliary clamp 19 and the spring actuated jaw 10 of clamp 7 100 100 and the cutter 13, to the dotted position 14^a, Fig. 1, at which time the cutter descends and severs the thread between the clamp 7 and needles 3, thereby bringing the splicing thread once more to its original position, as 105 shown.

The essential feature of my invention is the provision of the supplemental or auxiliary splice thread clamp 19, positioned to clamp the thread intermediate of the main 110 thread clamp 7 and the splice thread guide 15, the said auxiliary clamp 19 preferably at approximately right angles to the main clamp and acting to hold the thread sufficiently to relieve the strain upon the main 115 clamp 7, until the yarn takes the position 14^b, at which time it is drawn laterally from under the clamp plate 19 and its frictional contact with the needles at 14^c is sufficient to insure feeding of the yarn from the thread 120 guide 15; and thereafter, the danger of withdrawing the thread from the main clamp 7 before interknitting begins at A, is over. By the time the beginning of the interknitting reaches the position A, the end of the 125 thread 14 is withdrawn from clamp 19.

When the splice thread 14 is to go out of action, the thread guide 15 is raised, thereby causing the thread to pass above the needles and to the inner circular space, and as the 130

needle cylinder rotates, the thread is carried under the auxiliary clamp plate 19 and also under the plate 10 of the main clamp 7 and undercutter 13; thereupon the cutter descends and severs the thread between the clamp 7 and needles, once more bringing the splice thread to the position shown in Fig. 1.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim as new and desire to secure by Letters Patent, is:—

1. A knitting machine having a needle cylinder and needles therefor, a thread guide for feeding a body thread to the needles, a thread guide for feeding a splicing thread to the needles, means for putting the thread guides into and out of feeding action, a main thread clamp and cutter and supporting plate therefor arranged within the needle cylinder for respectively holding the thread ends and severing the threads between the clamp and fabric on the needles, combined with an auxiliary clamp arranged within the needle cylinder to provide additional clamping action upon the splicing thread, said auxiliary clamp arranged out of alignment

with the body thread and its guide, whereby an additional clamping of the splicing thread may be had to prevent it from becoming released from the main clamp at the time the splicing thread is fed to the needles and before it is knitted into the fabric.

2. The invention according to claim 1, further characterized by having the auxiliary splice thread clamp formed to act by gravity, whereby a substantially constant clamping pressure is obtained.

3. The invention according to claim 1, further characterized by the auxiliary clamp being made of a loosely supported bar resting upon a clamping edge of the plate supporting the main clamp.

4. The invention according to claim 1, wherein the additional auxiliary clamp for the splicing thread is angularly disposed in respect to the main clamp, whereby it applies a clamping action upon the splicing thread when extending substantially at right angles to the direction of the body thread leading to the main clamp.

5. The invention according to claim 1, wherein the auxiliary clamp for the splice thread comprises an elongated bar having a vertical slot in its middle and around the front portion, and held in place upon the frame of the main clamp and cutter by means of a screw extending through the vertical slot and while holding the clamping bar in position, permitting it to rise and fall under gravity action when clamping the splice thread.

In testimony of which invention, I hereunto set my hand.

PAUL H. FRYER.
